UNITED STATES PATENT OFFICE.

CARL P. NACHOD, OF PHILADELPHIA, PENNSYLVANIA, ASSIGNOR TO NACHOD SIGNAL COMPANY, INC., A CORPORATION OF NEW YORK.

SIGNALING SYSTEM.

1,223,413.

Specification of Letters Patent. Patented Apr. 24, 1917.

Application filed October 4, 1912. Serial No. 723,838.

To all whom it may concern:

Be it known that I, CARL P. NACHOD, a citizen of the United States, residing in the city of Philadelphia, county of Philadelphia, and State of Pennsylvania, have invented a new and useful Signaling System, of which the following is a specification.

My invention relates to a signal system adapted to control car or train movements upon a railway, and particularly upon an electric railway.

It is the object of my invention to provide a signaling system for a railway on which the cars or trains travel in one direction only, as for example in a double track railway, the system providing stop or caution or proceed indications, or all of them. And it is the further object of my invention in such a system to provide for such indications in a manner such that any failures in the circuits or apparatus will cause a minimum of danger to the traffic.

My invention resides in the system, features and apparatus hereinafter described and claimed.

For an illustration of some of the forms my invention may take reference is to be had to the accompanying drawings, in which:

Figure 1 is a diagram of the circuits and apparatus comprised in one form of my invention.

Fig. 2 is a vertical elevational view, partly in section, of a semaphore signal together with a diagram of its controlling circuits and apparatus.

Fig. 3 is a vertical elevational view, partly in section, of a modified form of semaphore signal together with a diagram of its controlling circuits and apparatus.

Fig. 4 is an elemental illustration of a modification of the semaphore controlling mechanism of Fig. 2.

Referring to Fig. 1, T represents a trolley wire, third rail, or other contact conductor of an electric railway system with which engages a traveling contact carried by a car or train for supplying current to the motors and other apparatus upon the car or train. Or the conductor T may be simply a signal system conductor connected with a suitable source of current, and extending along the path of travel of cars or trains upon a steam or other railway, the car or train in such case carrying a member which is adapted to op-

erate the several vehicle controlled contacts 55 or switches.

Disposed along the railway at suitable intervals are signal stations, several of which, for illustrating my invention, are here indicated at 1, 2 and 3. The signaling apparatus is preferably the same at each station, and is so here shown, corresponding parts at the different stations being indicated by the same reference characters with the addition of the subscripts 1, 2 and 3 to indicate at 65 which station located.

The signaling apparatus at station 1 will now be described, it being understood that the same description applies to the signaling apparatus at the other stations.

In electrical communication with the conductor T is a member a1 adapted to be engaged by a member carried by the moving car or train, car or train movements being assumed to be from left to right, and 75 brought into engagement with contacts b1 and c1. The contact c1 is connected with one terminal of the electro-magnet A1 whose other terminal is connected to earth or return conductor E. The armature d1 of magnet A1 is pivoted at its left end and is adapted to engage with its right end the notched wheel e1 secured upon shaft f1 upon which is secured the conducting disk g1 having the projection h1 normally in contact with the 80 brush i1 connected with the conductor T. Maintaining electric communication with the disk g1 is the brush j1 connected to one terminal of the magnet H1 whose other terminal connects to the earth or return conductor E. The electro-magnet C1 has one of its terminals connected to the earth or return conductor E and its other terminal to a conductor 4 extending to station 2 and connecting with contact b2. The magnet 95 C1 is provided with the armature k1, pivoted at its right end and adapted to engage the notched wheel e1 with its left end. The magnet H1 is provided with armatures m1 and n1 both electrically connected to the 100 conductor T. The armature m1 is adapted to contact with either of the contacts o1 or p1, o1 being connected with contact q1 and with a conductor 5 which extends to the first station to the left, not shown, and there 105 connecting with one terminal of an electro-magnet corresponding with electro-magnet M1. The contact p1 connects with one ter-

5 minal of a red incandescent electric lamp R1 whose other terminal is connected to earth or return conductor E. Armature n_1 is adapted to engage contact r_1 connected with contact s_1 . The electro-magnet M1 has one terminal connected to earth or return conductor E and its other terminal, by conductor 5 extending to station 2 and connected with the contacts o_2 and q_2 . The 10 electro-magnet M1 has two armatures t_1 and u_1 adapted to engage respectively the contacts q_1 and s_1 . The armature u_1 is connected to one terminal of a yellow incandescent electric lamp Y1 whose other terminal is 15 connected to earth or return conductor E; and the armature t_1 is connected with one terminal of a green incandescent electric lamp G1 whose other terminal is connected to the earth or return conductor E.

20 While I have shown the magnets H, and M, each controlling two armatures, it is to be understood that a single armature may be employed for each magnet, such single armature making and breaking the same circuits indicated.

25 When the magnet H1 is energized its armature m_1 engages contact o_1 and its armature n_1 engages contact r_1 ; and when the magnet H1 is deenergized its armature m_1 drops into engagement with contact p_1 and its armature n_1 falls away from contact r_1 . When the magnet M1 is energized its armature t_1 engages contact q_1 and its armature u_1 is held away from contact s_1 ; and when the magnet M1 is deenergized its armature t_1 separates from contact q_1 and its armature u_1 engages contact s_1 .

30 The operation is as follows:

35 When there is no car or train between stations 1 and 3, the parts are in the positions shown in Fig. 1 and the green lights G1, G2 and G3 are illuminated giving green signals at the three stations indicating that 40 the blocks at or near whose entry they are located are clear, so that a car or train may proceed.

45 If now a car or train pass station 1 from left to right into the block between stations 1 and 2, the member a_1 is brought into engagement with contacts b_1 and c_1 , allowing current to flow from conductor T through contact b_1 and the conductor 4 leading back to the C magnet at the station 55 in the rear and through contact c_1 through the winding of magnet A1 to the earth or return conductor E, energizing magnet A1 which then attracts its armature d_1 which steps the notched wheel e_1 around one notch 60 in a clockwise direction. This movement of the wheel e_1 rotates the conducting disk g_1 in like direction withdrawing the lug h_1 from contact with brush i_1 thus interrupting the circuit through the winding of the magnet 65 H1 which is accordingly deenergized allowing its armatures m_1 and n_1 to fall, m_1 engaging contact p_1 thus allowing current to flow from conductor T through armature m_1 , contact p_1 and red light R1 causing the same to glow and give a stop or danger signal at station 1 to any car or train which may be following. And the armature m_1 having separated from contact o_1 , interrupts the circuit from the conductor T through the armature m_1 , contact o_1 , contact q_1 , armature t_1 , and green lamp G1, thus causing the lamp G1 to cease to glow.

70 The red lamp R1 continues to glow so long as the car or train is between stations 1 and 2, and when the car or train arrives at station 2 the member a_2 is brought into engagement with contacts b_2 and c_2 . Current accordingly flows from conductor T through contact b_2 and conductor 4 back to station 1 and through the winding of the magnet C1 to earth or return conductor E, energizing said magnet C1 which then attracts its armature h_1 and steps the wheel e_1 backwardly in counter clockwise direction one notch again bringing lug h_1 into engagement with brush i_1 which again energizes the magnet H1, which then attracts its armatures m_1 and n_1 , the former separating from contact p_1 and reengaging contact o_1 thus interrupting the circuit through the red lamp R1. Simultaneously current flows through contact c_2 and the winding of magnet A2 which then attracts its armature d_2 and steps the wheel e_2 around one notch separating lug h_2 from brush i_2 . This causes deenergization of magnet H2 allowing armatures m_2 and n_2 to drop, the former closing the circuit through red lamp R2 through contact p_2 and breaking the circuit through the green lamp G2 at contact 80 o_2 . The separation of armature m_2 from contact o_2 accordingly interrupts the circuit from conductor T, through m_2 , contact o_2 , and conductor 5 extending back to magnet M1. Magnet M1 is accordingly deenergized 85 and drops its armatures t_1 and u_1 , t_1 in separating from contact q_1 interrupting the circuit of the green lamp G1, notwithstanding the fact that the armature m_1 has reengaged contact o_1 . The armature n_1 having 90 also reengaged contact r_1 , and armature u_1 having dropped and engaged contact s_1 , current flows from conductor T through armature n_1 , contact r_1 , contact s_1 , armature u_1 , through yellow lamp Y1 to earth or return conductor E, thus causing the lamp to glow and give a caution indication. Accordingly we have displayed at station 1 a caution signal Y1, at station 2 the stop or danger signal R2, and at station 3 the green clear 95 or proceed signal G3.

100 And the signals remain in this condition until the car or train reaches station 3 where it causes member a_3 to engage contacts b_3 and c_3 . Current will now flow from con-

ductor T through contact b_3 , conductor 4 back to magnet C2 and earth or return conductor E, energizing magnet C2 which then attracts its armature h_2 which turns the 5 wheel e_2 backwardly in counter clockwise direction one notch bringing lug h_2 into engagement with brush i_2 causing the magnet H2 to be again energized. It accordingly attracts its armatures m_2 and n_2 into re-
10 engagement with contacts o_2 and r_2 respectively. The result is that current will flow from conductor T through armature m_2 , contact o_2 , conductor 5 back to magnet M1 energizing the same to attract its armatures t_1 and u_1 . Accordingly u_1 separates from contact s_1 breaking the circuit of the yellow lamp Y1 and armature t_1 engages contact g_1 reestablishing circuit through lamp G1 which now glows and gives a clear
15 or proceed signal. Current simultaneously flows through contact c_3 and the winding of magnet A3 energizing the same to attract its armature d_3 which steps the wheel e_3 around one notch in clockwise direction
20 separating lug h_3 from brush i_3 thus de-energizing magnet H3 allowing armatures m_3 and n_3 to drop. As a result armature m_3 separates from contact o_3 breaking the circuit through the green lamp G3, and armature m_3 engages contact p_3 closing circuit through the red lamp R3 which now glows and gives a stop or danger signal. And since armature m_3 has separated from contact o_3 the circuit through conductor 5
25 extending back to magnet M2 is broken de-energizing magnet M2 and allowing armatures t_2 and u_2 to drop causing a further break in the circuit of the green lamp G2 and the closure of circuit at contact s_2
30 through the yellow lamp Y2 which now glows and gives a caution signal. Accordingly we have at station 1 a clear or proceed signal G1, at station 2 a caution signal Y2 and at station 3 a red stop or danger signal R3 displaying.
35 And so on as the car or train proceeds along the railway it discontinues the clear or proceed signal as it enters a block and sets a stop or danger signal, and changes the stop or danger signal at the entry to the block in the rear to a caution or yellow signal and at the entry to the second block in the rear changes the caution or yellow signal to a green clear or proceed signal.
40 If more than one car or train enters a block, as, for example, by passing and actuating the member a_1 , the first car or train on entering actuates the wheel e_1 one notch to remove lug h_1 from engagement with
45 brush i_1 interrupting the circuit of the magnet H1, as previously described, and each succeeding car or train causes the wheel e_1 to be stepped around a further notch in the same direction, but without any different
50 effect upon the magnet H1, the lug h_1 be-

ing merely farther and farther separated from the brush i_1 , continuing the deenergization of magnet H1. Then the first car or train leaving the block has by passing the member a_2 caused temporary energization of the magnet C1, as previously described, to step the wheel e_1 backward one notch. And each car or train so leaving the block causes temporary energization of the magnet C1, until the last car or train has returned the wheel e_1 to its normal position shown. In other words the apparatus is such that cars are counted into and out of a block and not until the last car leaves the block is the wheel e_1 restored to its normal condition.

The effect is that car counting occurs, as described, and with the entry of the first car to the block the green light G1 is extinguished and the red or stop signal R1 energized and it remains so energized until the last car has left the block when the red or stop signal will be changed to a yellow or caution signal.

If a car or train has entered a block, as, for example, by passing the member a_2 it causes the signal operation as hereinbefore described. If then it should back out of the block in reverse direction past the member a_2 , that member will be brought into engagement with contacts v_2 and w_2 causing current to flow from conductor T through contact v_2 and conductor 4 to energize magnet C2 to step the wheel e_2 backward one notch canceling the effect upon the wheel e_2 caused by the entry of the car into the block as by bringing the member a_2 into engagement with the contact e_2 . A current will simultaneously flow from conductor T through contact w_2 back through conductor 6 to the station in the rear and through magnet A1 stepping the wheel e_1 around in a clockwise direction to produce a state of affairs the same as if the car had passed member a_1 but had not passed member a_2 .

From the hereinbefore described system it will appear that failure of circuits or magnets will always result in a stop signal being displayed, or at least in the displaying of a signal less favorable for train movement than permitted by the signal showing before the failure. Thus if when both magnets H, and M, should be energized, either fails, the green signal will be discontinued and either a red signal or a yellow signal will be displayed, according as the H, or M, magnet above fails; or if both fail a red signal will be displayed.

In Fig. 2 I have shown an arrangement where a three position semaphore with three differently colored glasses or spectacles is employed in place of the electric signal lamps of Fig. 1 and magnets corresponding with magnets H1, M1, of Fig. 1, are em-

ployed to actuate the semaphore; and the arrangement is such that these magnets are both energized, or only one of them energized, or both deenergized.

- 5 The brush $i1$ is here connected to earth or return conductor E and the brush $j1$ connects through conductor 7 with one terminal of both magnets or solenoids M and H . The other terminal of the winding of solenoid M connects with conductor 8 extending to a switch controlled by the H magnet or solenoid at the next station to the right. The other terminal of the winding of solenoid H connects with contact x connected to conductor 9 in turn connected to the conductor T . Opposed to the contact x is the contact y connected to conductor 8 which extends to the left to the preceding station and connects to one terminal of the winding of solenoid M at the preceding station. The solenoid M is pivoted at 10 upon the casing 11 forming the base or pedestal for the semaphore mast 12 to which the semaphore 13 is pivoted at 14 . The core or armature 15 of the solenoid M is pivoted at 16 to the joint between the two links 17 and 18 , forming a toggle, the link 17 being pivoted at its other end at 19 to the bottom of the rod 20 extending upwardly through the mast 12 and provided at its upper end with a rack 21 meshing with the gear 22 which in turn meshes with the gear 23 secured to the semaphore 13 and having the pivot 14 as its axis of rotation. The link 18 is pivoted at 24 to the link 25 pivoted at 26 to the link 27 pivoted at 28 to the casing 11 or other fixed abutment. The links 25 and 27 also form a toggle, and the pivot pin 24 is guided in the vertical slot 29 in the fixed member 30 .
 40 The core or armature 31 of the solenoid H is pivoted to the toggle links 25 , 27 at 26 , and the solenoid H is itself pivoted at 32 to the casing 11 or other fixed part. The solenoid M has a coarse wire winding and a fine wire 45 connected in series with each other, the coarse wire winding being at the end nearer the pivot 10 . At the joint between the coarse and fine wire windings a connection is made by conductor 33 with the contact 34 opposed to which is the contact 35 connected to the remaining terminal of the fine wire winding which also connects with the conductor 8 . In the position shown the contacts 34 and 35 are in electrical communication with each 50 other through the core or a conducting ring carried thereby and insulated therefrom. Accordingly the fine wire winding is short-circuited. The magnet or solenoid H also has coarse and fine wire windings arranged 55 similarly to those of solenoid M . One terminal of the fine wire winding of solenoid H is connected to contact 36 and the other terminal thereof is connected to contact 37 which are in electrical communication with 60 each other in the position shown thus short-circuiting the fine wire winding. The solenoid M carries a bracket or projection 38 which supports the contacts 34 and 35 to cause them to remain in fixed relation with respect to the solenoid M notwithstanding 65 its movement upon the pivot 10 . And similarly the solenoid H has a bracket 39 which supports the contacts x , y and 36 , 37 in fixed relation with respect to the solenoid H notwithstanding 70 its movement upon the pivot 32 .
 75 When either of the solenoids M or H is energized a comparatively large current will flow through its coarse wire winding producing a powerful magnetic field which will attract its core toward the right. The movement of the core causes a straightening out of the associated toggle which accordingly causes an upward thrust upon the rod 20 which causes through the rack and gears a clockwise rotation of the semaphore 13 about 80 its pivot 14 . Near or at the completion of the stroke of the core the short-circuit of the fine wire winding is broken, bringing the fine wire winding into series with the coarse wire winding, greatly reducing the current 85 strength, which current strength is however sufficient to hold the core in its attracted position and therefore the toggle in its straightened position. The arrangement is such that neither toggle will be completely 90 straightened but will be slightly undertraveled, or under-set.
 95 It will be understood therefore that when both solenoids M and H are deenergized, the condition illustrated in Fig. 2, the semaphore 13 will be in the horizontal position indicating stop or danger, being biased to such position by gravity. If one of the solenoids is energized, its associate toggle will be extended and give sufficient upward movement to the rod 20 to cause the semaphore 13 to take a position substantially midway toward the vertical, that is at substantially 45° with the horizontal, to give a caution signal. And when both solenoids 100 are energized both toggles are extended causing a further upward movement of the rod 20 sufficient to bring the semaphore 13 to a vertical position, indicating clear or 105 proceed.
 110 As illustrated in Fig. 2, it is assumed that a car or train has passed into the block between stations 1 and 2 having brought member $a1$ into engagement with contact $c1$ to energize magnet $A1$ to step the notched 115 wheel $e1$ around one notch to separate lug $h1$ from brush $i1$ and therefore deenergizing both solenoids M and H , allowing the semaphore to move to the position shown to give a stop or danger signal. When the semaphore is in this position the red glass or spectacle Lr is in front of lamp 40 thereby showing a red light to give a stop or danger signal. When the train or car passes into 120 the next block the member $a2$ is brought into 125 130

engagement with contact b_2 causing current to flow from conductor T through contact b_2 conductor 4 back to station 1 and thence through the winding of magnet C1 to step the wheel e_1 backwardly one notch to bring lug h_1 into contact with brush z_1 . This will allow current to flow from conductor T through conductor 9 through the coarse wire winding of solenoid H energizing the same to extend toggle 25, 27 and move the semaphore 13 to the 45° or caution position. The solenoid M is not simultaneously energized because the circuit of the winding is broken through conductor 8 at contacts x and y of solenoid H at station 2, for, on the entry of the car or train to the block to the right of station 2 caused the deenergization of both solenoids M and H at station 2. Due to the energization of solenoid H at station 1 the contact, bridging contacts 36 and 37 in the position shown, is moved to the right with the core 31 to bridge contacts x and y . Accordingly when the car or train enters the next block to the right at station 3, not shown, the H solenoid at station 2 will be energized to give a caution signal at station 2 and will allow current to flow from conductor T through conductor 9 at station 2 through contacts x and y and through the conductor 8 back to station 1 and then through the winding of solenoid M to conductor 7, to lug h_1 and brush z_1 to earth E at station 1 energizing solenoid M at station 1. It being remembered that solenoid H was previously energized, now both solenoids are energized, semaphore 13 at station 1 will take the vertical position giving a clear or proceed indication.

40 And so on throughout the travel of a car or train along the railway, the semaphore at the entrance to a block will take the horizontal position; the semaphore at the entrance to the block in the rear will take the 45° position; and the semaphore at the entrance to the second block in the rear will take the vertical position.

When the semaphore takes the 45° position the yellow glass or spectacle L_y will come in front of the lamp 40 giving a yellow or caution indication; and when the semaphore is in the vertical position the green glass or spectacle L_g will come in front of the lamp 40 giving a clear or proceed indication.

45 In Fig. 3 a modified form of semaphore actuating mechanism is illustrated. In this case a downward pull upon a chain or cord 41 passing over the cam 42, the latter secured to semaphore 13 biased by gravity to the position shown, will move the semaphore 13 to the caution or clear or proceed positions. The cam is so shaped that the initial pull on chain 41 during the first part of solenoid core movement acts through a greater lever arm than during later stages of core movement. The cord or chain 41 is secured at its lower end to the core 15 of solenoid M which has coarse and fine wire windings, the coarse winding being the lower of the two. When the solenoid M is deenergized, as shown, the fine wire winding is short-circuited through contacts 34 and 35, and when the solenoid M is energized the attraction of its core 15 downwardly brings insulation between contacts 34 and 35 to break the short-circuit of the fine wire winding, throwing the same into series with the coarse winding, the current then being sufficient to hold the core 15 attracted. The solenoid M is secured to and supported upon the core 31 of the lower solenoid H which is fixed with respect to the pedestal of casing 11. The solenoid H has coarse and fine windings, the coarse winding being the lower of the two, and the fine wire winding is short-circuited when solenoid H is deenergized, as shown, through contacts 36 and 37; and when the solenoid H is energized after suitable movement of its core 31 downwardly insulation is brought between contacts 36 and 37 to break the short-circuit of the fine wire winding, throwing the same into series with the coarse winding, the resultant magnetism being sufficient to retain the core 31 attracted. The circuit arrangements are the same as those illustrated in connection with Fig. 2. When the solenoid H is energized, it attracts its core 31 downwardly carrying with it the solenoid M, a pull being transmitted through core 15 to cord or chain 41 to move the semaphore 13 to the 45° or caution position. When the solenoid M is thereafter energized it attracts its core 15 downwardly exerting a further pull upon the chain 41 which moves the semaphore 13 to the vertical position indicating clear or proceed. The order of energization of solenoids M and H, and of the deenergization of both of them, is the same as described in connection with Fig. 2.

50 In Fig. 4 a double toggle arrangement is shown for exerting a pull upon chain or cord 41 to perform the same operation performed by the chain or cord 41 of Fig. 3. In this case toggles 17, 18 and 25, 27 are actuated by solenoid cores 15 and 31, respectively, as shown in Fig. 2. Here however the pivot 19 is stationary in the bracket 43 secured upon the pedestal or casing 11. The pivot 24 is guided in slot 29 in the fixed member 30, and the lower pivot 28 slides in the slot 44 in the fixed member 30. Thus when core 31 is attracted by solenoid H the toggle 25, 27 is extended thrusting the pivot 28, to which the lower end of the chain or cord 41 is attached, downwardly pulling downwardly upon the cord or chain 31 and moving the semaphore to the caution or 45° position. When thereafter core 130

15 is attracted by solenoid M, toggle 17, 18 is extended pushing the previously extended toggle 25, 27 downwardly, the pivots 24 and 28 moving downwardly in slots 29 and 44 respectively causing a further pull upon the cord or chain 41 to move the semaphore to the vertical position indicating clear or proceed.

16 While I have herein shown certain means and arrangements for carrying out my invention, it is to be understood that many modifications may be resorted to without departing from the spirit and principle of my invention.

17 What I claim is:

1. The combination with a vehicle controlled switch and a block or section of a railway, an electro-magnet controlled by said switch, a step-by-step switch controlled by said magnet, a clear or proceed signal, second and third electro-magnets normally coöperating to display said clear or proceed signal, a second signal, said second electro-magnet being controlled by said step-by-step switch to discontinue display of said clear or proceed signal and to cause the display of said second signal.

2. The combination with a vehicle controlled switch and a block or section of a railway, an electro-magnet controlled by said switch, a step-by-step switch controlled by said magnet, a clear or proceed signal, second and third electro-magnets normally coöperating to display said clear or display signal, a second signal, said second electro-magnet being controlled by said step-by-step switch to discontinue display of said clear or proceed signal and to cause the display of said second signal, signaling apparatus at another station comprising an automatically controlled switch, said third electro-magnet controlled by said last named switch.

3. The combination with a vehicle controlled switch and a block or section of a railway, an electro-magnet controlled by said switch, a step-by-step switch controlled by said magnet, a clear or proceed signal, second and third electro-magnets normally coöperating to display said clear or display signal, a second signal, said second electro-magnet being controlled by said step-by-step switch to discontinue display of said clear or proceed signal and to cause the display of said second signal, signaling apparatus at another station comprising an automatically controlled switch, said third electro-magnet controlled by said last named switch, and a third signal displayed in response to normal condition of said second electro-magnet and abnormal condition of said third electro-magnet.

4. The combination with a vehicle controlled switch and a block or section of a railway, an electro-magnet controlled by said switch, a step-by-step switch controlled

by said magnet, a clear or proceed signal, second and third electro-magnets normally coöperating to display said clear or display signal, a second signal, said second electro-magnet being controlled by said step-by-step switch to discontinue display of said clear or proceed signal and to cause the display of said second signal, signaling apparatus at another station comprising an automatically controlled switch, said second electro-magnet being normally energized through said step-by-step switch, and said third electro-magnet being normally energized through said automatically controlled switch at another station.

5. The combination with a vehicle controlled switch and a block or section of a railway, a signal, normally energized electro-magnets coöperating to cause the display of said signal, a second signal, means controlled by said vehicle controlled switch upon the entry of a car or train into said block or section for deenergizing one of said electro-magnets, means responsive to deenergization of said electro-magnet for causing display of said second signal and for discontinuing the display of said first signal, a third signal, and means responsive to entry of a car or train into the block or section in advance of said first named block or section causing reenergization of said electro-magnet and deenergization of another of said electro-magnets to cause the display of said third signal and discontinuation of the display of said second signal, and means responsive to the entry of a car or train into the block or section in advance of said second block or section to reestablish display of said first signal and discontinue the display of said third signal.

6. The combination with a vehicle controlled switch and a block or section of a railway, of an electro-magnet controlled thereby, a second switch controlled by said electro-magnet, a second electro-magnet controlled by said second switch, a signal, a third electro-magnet in normal condition coöperating with said second electro-magnet to display said signal, said second switch operated in response to control of said first magnet by said first switch upon the entry of a car or train into said block or section to discontinue coöperation between said second and third electro-magnets to discontinue display of said signal, a second signal brought to display in response to said operation of said second electro-magnet, a third signal, and means responsive to entry of a car or train into a block or section in advance of said first named block or section restoring said second switch and second electro-magnet to their previous conditions and changing said third electro-magnet from its normal condition, and means responsive to the restoration of said second

- 5 electro-magnet to its said previous condition and alteration from normal condition of said third electro-magnet causing display of said third signal.

6 7. The combination with a vehicle controlled switch and a block or section of a railway, of an electro-magnet controlled thereby, a second switch controlled by said electro-magnet, a second electro-magnet normally energized through said second switch, a third normally energized electro-magnet, a signal, means controlled by said second and third electro-magnets for displaying said signal, said first electro-magnet shifting said second switch upon the entry of a car or train into said block or section to de-energize said second electro-magnet, a second signal, means displaying said second signal upon the deenergization of said second electro-magnet and discontinuing display of said first signal, a third signal, means responsive to the entry of a car or train into the block or section in advance of said first named block or section reenergizing said electro-magnet and deenergizing said third electro-magnet, and means responsive to such altered conditions of said second and third electro-magnets displaying said third signal.

10 8. In a signaling system, similar signaling apparatus at each of a plurality of separated stations, said apparatus at one station comprising a vehicle controlled switch, an electro-magnet controlled by said switch, a second switch controlled by said electro-magnet, a second electro-magnet controlled by said second switch, a third electro-magnet controlled by the second electro-magnet at another station, a plurality of signals and means at said one station displaying one or another of said signals controlled by said second and third electro-magnets, and a fourth electro-magnet for restoring said second switch.

15 9. In a signaling system, similar signaling apparatus at each of a plurality of separated stations, said apparatus at one station comprising a vehicle controlled switch, an electro-magnet controlled by said switch, a second switch controlled by said electro-magnet, a second electro-magnet controlled by said second switch, a third electro-magnet controlled by the second electro-magnet at another station, a plurality of signals, and means at said one station controlled by said second and third electro-magnets for displaying one or another of said signals, and a fourth electro-magnet for restoring said second switch, said first electro-magnet being controlled by forward movement of a car or vehicle at the same station and by backward movement of a car or train at a neighboring station.

20 10. In a signaling system, similar signaling apparatus at each of a plurality of separated stations, said apparatus at one station comprising a vehicle controlled switch, an electro-magnet controlled by said switch, a second switch controlled by said electro-magnet, a second electro-magnet controlled by said second switch, a third electro-magnet controlled by the second electro-magnet at another station, a plurality of signals and means controlled by said second and third electro-magnets for displaying one or another of said signals, and a fourth electro-magnet for restoring said second switch, said fourth electro-magnet controlled by backward movement of a car or train at the same station and by the forward movement of a car or train at a neighboring station.

25 11. The combination with a vehicle controlled switch, of signal apparatus at a station comprising means for giving a plurality of signal indications, electro-magnets at the same station having independent magnetic circuits and normally coöperating to control said means to give a clear or proceed indication, one of said electro-magnets being controlled by said vehicle controlled switch to affect said means to discontinue said clear or proceed indication and to give another of said signal indications, and signaling apparatus at another station comprising similarly coöperating electro-magnets, a switch controlled by one of said last named magnets, a second of said first-named coöperating electro-magnets controlled by said last named switch at said other station.

30 12. The combination with a vehicle controlled switch, of signaling apparatus at a station comprising a step-by-step switch controlled by said switch, means for giving a plurality of signal indications, a pair of electro-magnets coöperating to control said means, one of said electro-magnets controlled by said step-by-step switch to affect said means to change the signal indication, and a vehicle controlled switch at another station controlling said step-by-step switch and controlling the other of said electro-magnets to affect said means to give another signal indication.

35 13. The combination with a vehicle controlled switch, of signaling apparatus at a station comprising a step-by-step switch controlled by said switch, means for giving a plurality of signal indications, a pair of normally energized electro-magnets coöperating to control said means to give a signal indication, one of said electro-magnets controlled by said vehicle controlled step-by-step switch to affect said means to give a different indication, and a vehicle controlled switch at another station controlling the other of said electro-magnets to affect said means to give another signal indication.

40 14. The combination with a vehicle controlled switch, of signaling apparatus at a

14. The combination with a vehicle controlled switch, of signaling apparatus at a 130

station comprising means for giving a plurality of signal indications, an electro-magnet controlled by said switch, a second switch controlled by said electro-magnet, a pair of electro-magnets coöperating with each other to control said means, said second switch controlling one of said electro-magnets to affect said means to give a different signal indication, a switch at another station controlling said second switch and controlling the second magnet of said pair to affect said means to give another signal indication.

15. The combination with a vehicle controlled switch, of signaling apparatus at a station comprising means for giving a plurality of signal indications, an electro-magnet controlled by said switch, a second switch controlled by said electro-magnet, a pair of electro-magnets coöperating with each other to control said means, said second switch controlling one of said electro-magnets to affect said means to give a different signal indication, a switch and a second pair 25 of electromagnets at another station, having the same functions respectively as the electro-magnets of said first pair, said last named switch controlling the second magnet of said first named pair to affect said means 30 to give another signal indication, said switch at another station controlled by the first magnet of said pair of magnets at said other station.

16. In a signaling system, a plurality of 35 signal stations each provided with signal apparatus comprising means for giving three signal indications, a vehicle controlled switch, a step-by-step switch controlled by said switch, a pair of electro-magnets coöperating to control said means, said magnets normally coöperating to give a clear or proceed indication, said step-by-step switch controlling one of said electro-magnets to affect said means to give a stop signal, and the second magnet of a pair controlled from another station to affect said means to give a caution signal.

17. The combination with a block or section of a railway, of vehicle controlled 50 switches at different points thereof, a step-by-step switch, means for moving said switch in one direction controlled by one of said vehicle controlled switches by train movement in one direction and by another of said vehicle controlled switches by train movement in opposite direction, and signaling means controlled by said switch.

18. The combination with a block or section of a railway, of vehicle controlled 60 switches at different points thereof, a switch, means for moving said switch in one direction controlled by one of said vehicle controlled switches by train movement in one direction and by another of said vehicle controlled switches by train movement in oppo-

site direction, means for producing a plurality of signal indications, an electro-magnet controlled by said switch, and a second electro-magnet coöperating with said electro-magnet to control said means.

19. The combination with a block or section of a railway, of vehicle controlled switches at different points thereof, a switch, means for actuating said switch in one direction controlled by one of said vehicle controlled switches by train movement in one direction and by another of said vehicle controlled switches by train movement in opposite direction, means for producing a plurality of signal indications, an electro-magnet 80 controlled by said switch, a second electro-magnet normally coöperating with said electro-magnet to cause said means to give a signal indication, actuation of said switch causing said means to give another signal 85 indication, and means controlling said second electro-magnet to coöperate with said first electro-magnet after said actuation of said switch to cause said means to give a third signal indication.

20. The combination with a block or section of a railway, of vehicle controlled switches at different points thereof, a switch, means for actuating said switch in one direction controlled by one of said vehicle controlled switches by train movement in one direction and by another of said vehicle controlled switches by train movement in opposite direction, means for producing a plurality of signal indications, an electro-magnet 100 controlled by said switch, a second electro-magnet normally coöperating with said electro-magnet to cause said means to give a signal indication, actuation of said switch causing said means to give another signal 105 indication, and a remote switch controlling said second electro-magnet to coöperate with said first electro-magnet after actuation of said switch to cause said means to give a third signal indication.

21. In a signaling system, means for giving a plurality of signal indications, a switch, a pair of electro-magnets normally coöperating to cause said means to give a signal indication, the first of said electro-magnets controlled by said switch, a remote switch, the second of said electro-magnets controlled by said remote switch, means for actuating said first named switch to control said first magnet to cause said means to give a second signal indication, control of said second electro-magnet by said remote switch when said first electro-magnet is in normal condition causing said means to give a third signal indication.

22. In a signaling system, the combination with a switch, of an electro-magnet normally energized therethrough, a remote switch, a second electro-magnet normally energized therethrough, means for actuating said 130

- switches, said electro-magnets when both energized producing a signal indication, said first magnet when deenergized producing a second signal indication, and said second electro-magnet when deenergized cooperating with said first magnet when energized to produce a third signal indication, the magnetic circuits of said electro-magnets being independent of each other.
23. In a signaling system, a switch, a pair of electro-magnets normally cooperating to produce a signal indication, the first of said electro-magnets controlled by said switch, a remote switch, the second of said electro-magnets controlled by said remote switch, means for actuating said first named switch to control said first magnet to produce a second signal indication, control of said second electro-magnet by said remote switch when said first electro-magnet is in normal condition producing a third signal indication, and electro-magnets responsive to vehicle movements in opposite directions for actuating said first named switch in opposite directions.
24. In a signaling system, the combination with a switch, of an electro-magnet normally energized therethrough, a remote switch, a second electro-magnet normally energized therethrough, means for actuating said switches, said electro-magnets when both energized producing a signal indication, said first magnet when deenergized producing a second signal indication, said second electro-magnet when deenergized cooperating with said first magnet when energized to produce a third signal indication, and electro-magnets responsive to vehicle movements in opposite directions for actuating said first named switch in opposite directions.
25. In a signaling system, the combination with a switch, of a magnet for actuating the same in one direction in response to vehicle movement in one direction at a given point and in response to vehicle movement in opposite direction at another point, a second electro-magnet for actuating said switch in opposite direction in response to vehicle movements opposite to said aforementioned vehicle movements at said points, and signaling apparatus controlled by said switch.
26. In a signaling system, the combination with a switch, of a magnet for actuating the same in one direction in response to vehicle movement in one direction at a given point and in response to vehicle movement in opposite direction at another point, a second electro-magnet for actuating said switch in opposite direction in response to vehicle movements opposite to said aforementioned vehicle movements at said points, an electro-magnet controlled by said switch, means for producing a plurality of signal indications, a second electro-magnet, and a remote switch controlling said second electro-magnet.
27. In a signaling system, signaling apparatus comprising at one station a pair of co-operating electro-magnets, a signal circuit controlled by said electro-magnets when both are energized, another signal circuit controlled by said electro-magnets when one is energized and the other deenergized, and a third signal circuit controlled by one of said electro-magnets solely when deenergized, the magnetic circuits of said electro-magnets being independent of each other.
28. In a signaling system, signaling apparatus comprising at one station a pair of co-operating electro-magnets, a signal circuit controlled by said electro-magnets when both are energized, another signal circuit controlled by said electro-magnets when one is energized and the other deenergized, a third signal circuit controlled by one of said electro-magnets solely when deenergized, a switch at the same station controlling one of said electro-magnets, and a switch at another station controlling the other of said electro-magnets, the magnetic circuits of said electro-magnets being independent of each other.
29. In a signaling system, signaling apparatus comprising at one station a pair of co-operating electro-magnets, a signal circuit controlled by said electro-magnets when both are energized, another signal circuit controlled by said electro-magnets when one is energized and the other deenergized, a third signal circuit controlled by one of said electro-magnets solely when deenergized, a step-by-step switch at the same station controlling one of said electro-magnets, and a switch at another station controlling the other of said electro-magnets.
30. In a signaling system, signaling apparatus at each of a plurality of stations, comprising a pair of electro-magnets, a switch at the same station with and controlling the first of said electro-magnets, means for normally energizing said first electro-magnet through said switch, a signal controlling switch controlled by said electro-magnet for normally giving a certain indication, vehicle operated means for opening the first mentioned switch to produce a second indication of the signaling means, a switch controlled by the first electro-magnet at another station through which the second electro-magnet at the first station is normally energized, means for opening the circuit of said second electro-magnet, to produce in conjunction with the deenergization of the first electro-magnet at the first station a third indication of said signaling means.
31. In a signaling system, signaling apparatus at each of a plurality of stations, comprising a pair of normally energized electro-magnets, a switch at one station controlled by the first of said electro-magnets at that station, signaling means controlled by said

- switch and normally giving a certain indication, vehicle controlled means for de-energizing said first electro-magnet to produce a second indication of the signaling means, a switch controlling the second of said electro-magnets and controlled by the first electro-magnet at another station, means for deenergizing said first electro-magnet at said second station to cause de-energization of the second electro-magnet at the first station, to produce in conjunction with the deenergization of the first electro-magnet at the first station a third indication of said signaling means.
32. In a signaling system, signaling apparatus at each of a plurality of stations comprising a pair of electro-magnets, a switch at the same station controlling the first of said electro-magnets, a signal controlling switch controlled by said first electro-magnet, a switch controlled by the first electro-magnet at another station controlling the second electro-magnet at said same station, said second electro-magnet coöperating with said first electro-magnet in producing a plurality of signal indications, and a third signal indication produced by said first electro-magnet solely.
33. In a signaling system, signaling apparatus at each of a plurality of stations comprising a pair of electro-magnets, a step-by-step switch at the same station with and controlling the first of said electro-magnets, a stepping electro-magnet for said step-by-step switch, a vehicle controlled switch at the same station with and controlling said stepping electro-magnet, a signal controlling switch controlled by the first of said pair of electro-magnets, and a switch controlled by the first of said pair of electro-magnets at another station controlling the second of said pair of electro-magnets at said first mentioned station.
34. In a signaling system, signaling apparatus at each of a plurality of stations comprising a pair of electro-magnets, a step-by-step switch at the same station with and controlling the first of said electro-magnets, signal controlling switches controlled by said electro-magnets, a switch controlled by the first electro-magnet at another station controlling the second electro-magnet at the first mentioned station, and means responsive to vehicle movements in opposite directions for actuating said step-by-step switch in opposite directions.
35. In a signaling system, step-by-step signal controlling/mechanism at each of a plurality of stations, said step-by-step mechanism comprising electro-magnets for actuating the same in opposite directions, and an associated vehicle controlled switch responsive to vehicle movement in one direction for controlling one of said magnets for moving said step-by-step mechanism in one direction and simultaneously controlling a magnet at another station for moving the step-by-step mechanism thereat in opposite direction, said switch being responsive to vehicle movement in opposite direction for controlling one of said electro-magnets.
36. In a signaling system, step-by-step signal controlling mechanism at each of a plurality of stations, said step-by-step mechanism comprising electro-magnets for actuating the same in opposite directions, and an associated vehicle controlled switch responsive to vehicle movement in one direction for controlling one of said magnets for moving said step-by-step mechanism in one direction and simultaneously controlling a magnet at another station for moving the step-by-step mechanism thereat in opposite direction, said vehicle controlled contact in response to vehicle movement in opposite direction controlling the others of said magnets at said stations.
37. The combination with a vehicle controlled switch, of a three-indication signaling means, a pair of electro-magnets whose magnetic circuits are independent of each other, said electro-magnets being located at the same station, movable means for each of said pair of electro-magnets and respectively controlled thereby, controlling said signaling means, said switch controlling one of said pair of electro-magnets, each of said movable means having two operative positions only, a second vehicle controlled switch at another station controlling the other of said pair of electro-magnets, whereby said signaling means may be caused to give any one of its three indications dependent upon the positions of said movable means.
38. Signaling means comprising the combination with a vehicle controlled switch, of a pair of electro-magnets, three signals, indicating danger, caution and safety respectively, a pair of switches controlled by said electro-magnets respectively, said danger signal being controlled by one of said switches only and each of the other two signals being controlled by both of said switches, deenergization of the one of said magnets which controls said one of said switches causing said danger signal to be displayed.
39. Signaling means comprising the combination with a vehicle controlled switch, of a pair of electro-magnets, one of which is controlled by said vehicle controlled switch, three signals indicating danger, caution and safety respectively, a pair of switching mechanisms controlled by said electro-magnets respectively, said danger signal being controlled by one of said switching mechanisms only and each of the other two signals being controlled by both of said switching mechanisms conjointly, means for normally energizing said electro-magnets, said switch-

ing mechanisms being so connected with said signals that deenergization of the one of said electro-magnets which controls said one of said switching mechanisms will cause the danger signal to be displayed.

40. Signaling means comprising the combination with a vehicle controlled switch, of a pair of electro-magnets, one of which is controlled by said vehicle controlled switch, three signals indicating danger, caution and safety respectively, a pair of switching mechanisms controlled by said electro-magnets respectively, said danger signal being controlled by one of said switching mechanisms only and each of the other two signals being controlled by both of said switching mechanisms, means for normally energizing said electro-magnets, said switching mechanisms being so connected with said signals that a deenergization of either of said electro-magnets will prevent the display of the safety signal.
41. Signaling means comprising the combination with a vehicle controlled switch, of a pair of electro-magnets, one of which is controlled by said vehicle controlled switch, three signals indicating danger, caution and safety respectively, a pair of switching mechanisms controlled by said electro-magnets respectively, said danger signal being controlled by one of said switching mechanisms only and each of the other two signals being controlled by both of said switching mechanisms, means for normally energizing said electro-magnets, all of said apparatus being at one signaling station, a second vehicle controlled switch at a second station controlling one of said electro-magnets, said switching mechanisms being so connected with said signals that the deenergization of one of said electro-magnets will prevent the

display of the safety signal and the deenergization of the other of said electro-magnets will cause the display of the danger signal and will prevent the display of the safety signal.

42. The combination with a pair of electro-magnets at the same station, of movable means respectively operated thereby, each of said movable means having two operative positions, a three-indication signaling means controlled by said movable means, the magnetic circuits of said electro-magnets being independent of each other, and vehicle controlled means for controlling said electro-magnets, whereby said signaling means may be caused to give any one of its three indications dependent upon the positions of said movable means.

43. The combination with a pair of electro-magnets at the same station, of movable means respectively operated thereby, each of said movable means having two operative positions, a three-indication signaling means controlled by said movable means, vehicle controlled means for controlling said electro-magnets, whereby said signaling means may be caused to give any one of its three indications dependent upon the positions of said movable means, said movable means automatically moving to such position when the electro-magnets are deenergized that the signaling means will display the danger signal.

In testimony whereof I have hereunto affixed my signature in the presence of the two subscribing witnesses.

CARL P. NACHOD.

Witnesses:

FLORENCE RUSH,
E. T. McCALL.

It is hereby certified that in Letters Patent No. 1,223,413, granted April 24, 1917, upon the application of Carl P. Nachod, of Philadelphia, Pennsylvania, for an improvement in "Signaling Systems," errors appear in the printed specification requiring correction as follows: Page 7, line 73, claim 10, after the word "signals" insert a comma; same page, line 123, claim 13, strike out the words "vehicle controlled"; and that the said Letters Patent should be read with these corrections therein that the same may conform to the record of the case in the Patent Office.

Signed and sealed this 29th day of May, A. D., 1917.

[SEAL.]

F. W. H. CLAY,

Acting Commissioner of Patents.

Cl. 246 38.
